G. B. Maynader
John R. Snow,

Inventor:

Charles Fred. Sleeper.

UNITED STATES PATENT OFFICE.

CHARLES F. SLEEPER, OF BOSTON, ASSIGNOR TO TATE & CO., OF MALDEN, MASSACHUSETTS.

DEVICE FOR HOLDING CORD, TAPE, &c.

SPECIFICATION forming part of Letters Patent No. 278,615, dated May 29, 1883.

Application filed June 3, 1882. (No model.)

To all whom it may concern:

Be it known that I, CHARLES FREDERIC SLEEPER, a citizen of the United States, residing at Boston, in the county of Suffolk and 5 State of Massachusetts, have invented a Device for Preventing the Unrolling of Cord, Tape, &c., from Spools, of which the following is a specification.

This invention consists in the improved device hereinafter described and claimed, whereby a coil of cord or tape may be conveniently suspended from a fixed rod or support, so that the cord or tape may be readily drawn off as required.

15 Of the accompanying drawings, forming a part of this specification, Figure 1 represents a side view of a device embodying my invention. Fig. 2 represents an edge view of the same. Fig. 3 represents an edge view of the 20 supporting device detached.

The same letters of reference indicate the same parts in all the figures.

In the drawings, R represents a reel of suitable construction, preferably composed of a 25 cylinder having two flanges, between which a coil of cord or tape, t, is wound.

In carrying out my invention I provide the reel with a supporting device composed of a continuous piece of metal wire bent to form 30 arms 2 2 at opposite sides of the reel and pivots 3 3 at right angles to said arms, and entering the center of the reel, so that the latter can rotate on said pivots, a U-shaped arm or cross-piece, 5, connecting the arms 2 2 and projecting downwardly from said arms toward the coil of cord or tape on the reel, and coils or 35 loops b' b', connecting the arms 2 2 with the branches of the arm 5, and constituting eyes

which may receive a fixed horizontal rod, from which the device may be suspended. The central portion, a, of the U-shaped arm 5 bears 40 with a yielding pressure on the periphery of the coil.

It will be seen that the coils or loops b' b' serve both to receive a fixed pivot or support, 45 and also as springs to press the arm 5 inwardly toward the coil of cord.

The reel suspended by the loops b' b' from a fixed support can be very conveniently operated when it is desirable to unwind a portion 50 of the cord, and it is always ready for use.

I do not claim a curved wire spring pivoted to a spool and arranged to press on the periphery of the material wound thereon, as I am aware that such a device is not new, it having 55 been used to hold a coil of flat tape.

I claim—

1. The combination, with the reel R, of the supporting device having the arms 2 2 at opposite sides of the reel, the pivots 3 3 on said 60 arms entering the center of the reel, the connecting-arm or cross-bar 5, and the coils or loops b' b', forming eyes adapted to receive a fixed rod or pivot from which the device may be suspended, as set forth. 65

2. In combination with the flanged reel R, the spring holding device 2 2 b' 3, the part 3 lying between the flanges of the reel and the parts 2 2 extending outside of the flanges of the reel, and being bent to enter the center 70 thereof, as set forth.

CHARLES FRED. SLEEPER.
